THREAD AND TUBE PROTECTOR

Raymond A. Phillips, Cleveland, Ohio, assignor to Protector Products Inc., Cleveland, Ohio, a corporation of Ohio

Application May 29, 1950, Serial No. 164,980

8 Claims. (Cl. 138—96)

This invention relates to protector caps for covering and protecting the plain or threaded ends of pipes, tubes, and the like, while performing various operations thereon, and during packing, shipping, and handling of the same.

The general object of the invention is to provide a new and improved thread protector.

A more specific object of the invention is to produce a metal thread protector having a soft lining held therein more securely than in prior art devices of this character.

Another specific object of the invention is to provide an improved thread protector and liner assembly that may be formed with a single stamping operation of a punch press or the like, whereby the assembly of separately formed metal shells and liners is eliminated.

Characteristic features of the method aspect of the invention are the simultaneous severing of plates or discs of metal and liner material from superposed sheets thereof and movement of severed metal and liner plates or discs together against a mandrel or stake, followed by pressing the two plates or discs together over the end of the mandrel, substantially without drawing the metal and in such manner as to fold the metal forming the sides of the resulting metal shell and to lock compressed portions of the liner between the folds of the metal.

The resulting thread protector, in the form of a generally cylindrical metal shell having one end open and the other end closed, or partially closed, is characterized by longitudinal folds in the side wall of the shell that begin at the open end thereof and terminate short of the closed or partially closed end thereof. The thread protector is also characterized by a liner that covers the interior surface of the metal shell and that is gathered or bunched between the folds in the side wall of the metal shell so as to be securely held against removal or slipping with respect to the metal shell.

Further objects, advantages and features of the invention will become apparent from the following more detailed description of an illustrative form of the device and a preferred method of making the same, and from the accompanying drawing in which—

Figure 1 is a plan view of the threaded end of a length of pipe with a thread protector embodying the present invention applied thereto, portions of the thread protector and pipe being broken away to show the interior construction of the thread protector and its relationship with the pipe;

Fig. 2 is an end elevation of the thread protector shown in Fig. 1, looking at the open end thereof with the pipe removed.

Fig. 3 is a fragmentary longitudinal section through the thread protector of Figures 1 and 2, the plane of the section being indicated by the line 3—3 in Fig. 2; and

Fig. 4 is a vertical section through a die and punch assembly for forming thread protectors of the type illustrated in Figures 1 to 3 and showing sheets of metal and lining materials in position for stamping blanks therefrom and showing folded blanks of the metal and lining materials as they appear in the die assembly at the conclusion of the forming operation.

Referring first to Fig. 1 the protector cap of the invention preferably comprises a generally cup-shaped metal shell 10, entirely open at one end and at least partially closed at the opposite end by a radially inwardly directed end wall 11. The end wall 11, in this instance, is shown as having a large aperture therethrough so that this wall, in effect, takes the form of an inwardly directed annular flange.

2

Completely covering the interior surface of the shell 10, including the interior of the end wall 11, is a liner 12 that is preferably formed from a relatively soft, compressible or deformable, and substantially inelastic sheet material, such as kraft paper, paperboard, a plastic film, sheet lead, sheet aluminum, or the like. This liner is preferably sufficiently soft to permit the shell to be forced over the threaded end of a pipe 13.

This composite cap of metal and soft lining material is preferably formed from flat sheets in a single stamping operation, as hereinafter more fully described. The manner in which this stamping operation is performed avoids any substantial drawing of the metal and shapes the flat sheet materials by folding them as they are drawn snugly around the sides of the mandrel or stake of a suitable die assembly. As best shown in Figs. 1 and 2, the folds 14 begin at the open end of the cap and extend in an axial direction in the side wall thereof, terminating short of the closed or partially closed end of the cap. Because of the symmetry of the forming mechanism, there is generally some semblance of regularity in the size, shape, and spacing of the folds 14, but precise regularity is not particularly sought.

The nature of the individual folds 14 may best be described as double reverse bends. Considering any one of these double reverse folds, as viewed in Fig. 2, an outermost cylindrically curved metal portion 16 is first reversely bent back upon itself to form an intermediate fold section 17, which is then bent back upon itself a second time to form an innermost cylindrical portion 18. Now, considering the next adjacent double reverse fold in either direction from the one first considered, it will be observed that it is formed in the same manner as the first but that each bend is directed oppositely to the corresponding bend in the first. Thus, the directions of folding of alternate double reverse bends around the cap are the same and the folding of the intermediate double reverse bends is in opposite directions.

The lining material 12 is somewhat similarly folded, to a degree, but the folding of the liner is generally so irregular as to present no clearly discernible repeating pattern. In the course of the folding operation, the non-resilient, soft and compressible lining material is forced to conform to the interior contour of the metal shell, being bunched or gathered in a rather highly compressed condition into all of the spaces between adjacent folds of the metal shell. The interior surface of the liner is relatively smooth and is more accurately cylindrical than either surface of the folded metal shell, but is covered with an irregular pattern of tightly compressed creases predominantly running generally axially thereof and producing only slight surface indentations and ridges, as indicated in Fig. 3.

The packing of the substantially non-resilient lining material tightly into the spaces between folds of the metal shell causes the liner to be firmly gripped thereby and held in place. However, if desired, this gripping action may be supplemented by the use of a thin layer of adhesive between the metal and the liner.

The finished cap should be somewhat larger in its inside diameter at the open end thereof than at the opposite end to produce a taper more or less conforming to the normal taper of pipe threads. This taper may be continuous from end to end of the cap or may start at a point 38 intermediate the ends of the cap, as best shown in Figs. 3 and 4. Thus, as the cap is forced over the end of a pipe or tube, the lining material will yield and be slightly deformed, being forced to conform to the surface of the pipe or tube by the gripping action of the metal shell.

The rigidity of the cap is increased by the longitudinally extending folds in the cylindrical side wall of the shell, and these reinforcing folds contribute materially to the force with which the cap grips the end of a pipe or tube to which it is applied.

According to the invention, the above described cap and the liner forming a part thereof are formed in their assembled relationship by a single stamping operation. Suitable stamping tools for this operation essentially comprise a die 21 having a cylindrical opening 22 therein; an annular punch 23 having cylindrical inner and outer contours and adapted to move into the cylindrical die open-

ing 22 with small clearance for shearing discs from sheet material passed between the die and the punch; a tapered, generally cylindrical stake or mandrel 24 concentrically disposed within the die opening 22 with the upper end of the mandrel disposed slightly below the upper end of the die opening 22; and an inner punch 26 concentrically mounted within the first mentioned punch 23. In the event a cap having a completely closed end is desired, the inner punch 26 may be omitted and the mandrel 24, which is shown with a central bore 27 for accommodating the inner punch 26, may be made as a solid piece.

These tools may be assembled upon a base 39, the mandrel 24 being outwardly flanged at its lower end to provide a seat 31 for the die 21. The seat 31 is provided with a pair of apertures 32 at diametrically opposite points for accommodating a plurality of pins 33 mounted therein for vertical sliding movement and preferably urged upwardly in a well known manner by suitable springs or hydraulic cushioning means (not shown). The upper ends of the pins 33 bear against an ejecting ring 34 that is disposed within the die 21 and surrounds the mandrel 24 with a free-sliding fit. The ejecting ring 34 is normally urged upwardly by the spring actuated pins 33 and is held with an annular shoulder 36 on the ejecting ring in engagement with an interior annular shoulder 37 of the die 21.

The outer contour of the mandrel 24 is cylindrical over most of its length but tapers from a point 38 to the upper end thereof to provide substantially greater clearance between the mandrel and the inner cylindrical surface of the punch 23 at the upper end of the mandrel than below the point 38 where the taper begins.

The inner punch 26 and the outer punch 23 are rigidly mounted for movement together, and a sleeve 41 is slidably mounted around the inner punch 26 and inside the outer punch 23. The sleeve 41 is normally held downwardly with its lower end even with the lower end of the outer punch 23 in any suitable manner, as by a spring or hydraulic control (not shown), so that the sleeve 41 engages the work at the same time as the outer punch 23 and moves therewith during the first punching operation and until punched discs are carried downwardly against the end of the mandrel 24. The sleeve 41 is then stopped and serves to hold the punched discs firmly in place against the mandrel during the remainder of the punching and forming operation.

A metal sheet 43 and a sheet of lining material 44 disposed together in superposed relationship are fed over the die opening 22. These sheets may be adhered together by a suitable adhesive or may be merely fed together as desired. When the punch assembly is lowered, the outer punch 23 severs discs from the metal sheet 43 and the liner sheet 44 simultaneously, and the outer punch 23 and sleeve 41 move the severed discs downwardly onto the mandrel 24 while the die 21 maintains the discs in registry. The sleeve 41 exerts a constant downward pressure against the discs opposite the periphery of the upper end of the mandrel as the downward movement of the outer die 23 is continued to the lowermost position, illustrated in Fig. 4. During the latter part of this movement the inner punch 26 punches an aperture through both of the discs, and the severed blanks drop downwardly through the hollow mandrel and out of the die assembly. In the event an aperture in the end of the cap is not desired, a solid mandrel is employed and the inner punch 26 is omitted. In this case, a solid rod is preferably substituted for the sleeve 41 so that the pressure applied to the metal sheet thereby will be applied entirely over the upper end of the mandrel.

The minimum clearance between the outer punch 23 and the mandrel 24 below the tapered portion of the mandrel should be at least three times the initial thickness of the metal sheet 43. The clearance above the point 38 where the taper of the mandrel begins, is substantially greater than the minimum clearance, as illustrated in Fig. 4. With this large clearance between the outer punch 23 and the mandrel 24, little drawing of the discs is effected as they are formed over the mandrel 24. Since the force exerted upon the upper surface of the metal disc by the outer punch 23 is substantially uniformly distributed entirely around its periphery throughout the forming operation, the metal tends to fold in the manner described above and shown in Figures 1 and 2, and the lower edges 46 and 47 of the resulting cap lie almost in the same plane.

The lower inner edge of the punch 23 is preferably

rounded, as shown at 49, to slide smoothly over the metal being formed as the direction of the force of the die on the metal being formed is directed more and more in a radially inward direction as the rounded edge of the punch passes downwardly over and beyond the periphery of the partially formed cap.

As long as the minimum clearance between the outer punch 23 and the mandrel 24 below the taper of the mandrel does not exceed three times the initial thickness of the metal sheet 43, the folds in the sides of the metal shell will be tightly creased, as shown in Fig. 2, and the lining material will be tightly packed and compressed so as to completely fill the spaces between adjacent folds in the metal shell.

The clearance between the inner punch 26 and the bore 27 of the mandrel 24 is preferably slightly greater than that required to produce a clean shearing cut. As a result, the inner edge of the flange 11 of the metal shell is turned downwardly over the adjacent edge of the liner, as shown at 48. This provides an additional barrier against slippage of the liner within the metal shell.

Where an aperture in the end of the cap is desired, the diameter of the aperture is preferably selected slightly larger than the interior diameter of the pipe to which the cap is to be applied. This prevents the cap from obstructing the interior bore of the pipe to any degree and permits various operations to be performed upon the interior of the pipe after it has been threaded and the cap has been applied over the threads.

Upon withdrawal of the punch assembly from the die 21, the ejector ring 34 follows the punch 23 upwardly until the shoulder 36 of the ring engages the shoulder 37 of the die. During upward movement of the ring 34, it engages the lower edge 46 of the metal shell of the cap, and lifts the cap upwardly off the mandrel 24. This frees the finished cap so that it can be lifted out of the die 21 either manually or mechanically, as desired.

The particular embodiments of the invention shown and described in detail herein involve caps having the general shape of a circular cylinder that is formed from discs (circular plates) of metal and lining material. It will be apparent, however, that caps having oval, polygonal, or other cross-sectional outlines, may readily be formed in the same manner from appropriately shaped plates of metal and lining material. Such other shapes are desirable for application to the ends of correspondingly shaped rods, tubes, and the like.

Accordingly, in this specification and in the appended claims, unless the context otherwise requires, the term "cylindrical" is intended to be construed in its broad geometrical sense and to cover the various shapes generated by a straight line generatrix as it moves normal to itself along a closed path, whether oval, elliptical, polygonal, or irregular in outline.

The thread protectors manufactured in accordance with the present invention may be applied over the ends of either threaded or unthreaded pipes, rods, tubes, or the like, and will firmly grip the same and be retained securely thereon. They may be applied in a simple manner by merely jamming them over the ends of members to be protected, either manually, preferably using a mallet or hammer, or automatically by any suitable ram mechanism.

From the foregoing description of the thread protectors manufactured in accordance with the present invention and of the preferred method of forming the same, it will be apparent that a novel and meritorious product has been provided and that the novel method of forming the same renders its production rapid, efficient and economical.

While the invention has been illustrated and described with reference to particular embodiments of the product and method, it will be apparent that numerous variations in both the product and method may be made without departing from the true spirit and scope of the invention.

This application is a continuation in part of my co-pending application Serial No. 85,580, filed April 5, 1949, for a Thread and Tube Protector, now abandoned.

Having described my invention, I claim:

1. A thread protector comprising an outer cup-shaped metal cap of generally cylindrical form having a plurality of double reverse folds in the side wall thereof spaced circumferentially around the cap and extending longitudinally thereof, and a continuous liner of a relatively soft sheet material covering the inner surface of

said cap and having portions bunched between and tightly gripped by adjacent pairs of said folds.

2. A thread protector comprising an outer cup-shaped metal cap of generally cylindrical form having a plurality of double reverse folds in the side wall thereof spaced circumferentially around the cap and extending longitudinally thereof, and a continuous liner of a relatively soft sheet material covering the inner surface of said cap and having portions bunched between and tightly gripped by adjacent pairs of said folds, the side wall of said cap adjacent the closed end thereof being tapered toward said closed end.

3. A thread protector comprising a generally cylindrical metal shell having one end open and the opposite end partially closed by a flange extending radially inwardly, the generally cylindrical wall of said shell having a plurality of axially extending double reverse folds therein, said folds beginning at the open end thereof and terminating short of the partially closed end thereof, and a continuous liner of a relatively soft sheet material covering the interior surface of said metal shell and being bunched between and tightly gripped by adjacent pairs of said folds.

4. A thread protector comprising a generally cylindrical metal shell having one end open and the opposite end partially closed by a flange extending radially inwardly, the generally cylindrical wall of said shell having a plurality of axially extending double reverse folds therein, said folds beginning at the open end thereof and terminating short of the partially closed end thereof, and a continuous liner of a relatively soft sheet material covering the interior surface of said metal shell and being bunched between and tightly gripped by adjacent pairs of said folds, said flange having an inner edge turned inwardly in an axial direction over the adjacent edge of said liner.

5. A thread protector comprising a generally cylindrical metal shell having one end open and the opposite end partially closed by a flange extending radially inwardly, the generally cylindrical wall of said shell having a plurality of axially extending double reverse folds therein, said folds beginning at the open end thereof and terminating short of the partially closed end thereof, and a continuous liner of a relatively soft sheet material covering the interior surface of said metal shell and being bunched between and tightly gripped by adjacent pairs of said folds, the generally cylindrical wall of said shell being tapered for a portion of its length adjacent and toward the partially closed end thereof.

6. A thread protector comprising a generally cylindrical metal shell having one end open and the opposite end partially closed by a flange extending radially inwardly, the generally cylindrical wall of said shell having a plurality of axially extending double reverse folds therein, said folds beginning at the open end thereof and terminating short of the partially closed end thereof, and a continuous liner of a relatively soft sheet material covering the interior surface of said metal shell and being bunched between and tightly gripped by adjacent pairs of said folds, the generally cylindrical shell, adjacent the partially closed end thereof, being tapered inwardly toward said flange, and said flange having an inner edge turned inwardly in an axial direction over the adjacent edge of said liner.

7. A thread protector comprising a generally cylindrical metal shell that is substantially circular in cross section and is at least partially closed at one end by a radially inwardly extending wall and open at the opposite end, the generally cylindrical wall being longitudinally folded into tightly creased double reverse folds at a plurality of locations spaced around the circumference thereof, alternate ones of said double reverse folds beginning with a fold under and circumferentially back in one direction, and the remainder beginning with a fold under and circumferentially back in the opposite direction, and a continuous liner of relatively soft sheet material covering the inner surface of said shell and adhered thereto, said liner being bunched into compressed portions filling the interior spaces between adjacent oppositely bent folded portions of the shell and being tightly gripped thereby.

8. The thread protector of claim 1 in which said liner is adhered to said metal shell.
